US00D999079S

(12) **United States Design Patent** (10) Patent No.: **US D999,079 S**
Wernimont et al. (45) Date of Patent: **** Sep. 19, 2023**

(54) **SENSOR MODULE**

(71) Applicant: **Hill's Pet Nutrition, Inc.**, Topeka, KS (US)

(72) Inventors: **Susan Wernimont**, Lawrence, KS (US); **Ryan Talley**, Topeka, KS (US); **Jodi Vondran**, Wamego, KS (US); **Stephen John French**, Lawrence, KS (US); **Cheryl Stiers**, Holton, KS (US); **Mark Neavitt**, Topeka, KS (US); **John Michael McCoy, Jr.**, Topeka, KS (US)

(73) Assignee: **Hills Pet Nutrition, Inc.**, Topeka, KS (US)

(**) Term: **15 Years**

(21) Appl. No.: **29/869,097**

(22) Filed: **Dec. 21, 2022**

Related U.S. Application Data

(62) Division of application No. 29/746,723, filed on Aug. 17, 2020, now Pat. No. Des. 976,730.

(57) **CLAIM**

The ornamental design for a sensor module, as shown and described.

DESCRIPTION

FIG. 1 is a front perspective view of a sensor module according to a first embodiment of the new design;

FIG. 2 is front view thereof;

FIG. 3 is a rear view thereof;

FIG. 4 is a right side view thereof;

FIG. 5 is a left side view thereof;

FIG. 6 is a top view thereof;

FIG. 7 is bottom view thereof;

FIG. 8 is a front perspective view of a sensor module according to a second embodiment of the new design;

FIG. 9 is front view thereof;

FIG. 10 is a rear view thereof;

FIG. 11 is a right side view thereof;

FIG. 12 is a left side view thereof;

FIG. 13 is a top view thereof;

FIG. 14 is bottom view thereof;

FIG. 15 is a front perspective view of a sensor module according to a third embodiment of the new design;

FIG. 16 is front view thereof;

FIG. 17 is a rear view thereof;

FIG. 18 is a right side view thereof;

FIG. 19 is a left side view thereof;

FIG. 20 is a top view thereof; and,

FIG. 21 is a bottom view thereof.
